Sims String Decelerator by Archery FS Discount Archery Product, published on the website of FS Discount Archery Product (Tustin, CA, USA) published on Feb. 11, 2015. <http://www.fsdiscountarchery.com/simsstringdeceleratornew.aspx>.

Primary Examiner — Michael A Pratt*(74) Attorney, Agent, or Firm* — Mathieu Audet(57) **CLAIM**

The ornamental design for a vibration absorber, as shown.

DESCRIPTION

FIG. 1 is an isometric view of the vibration absorber; FIG. 2 is a rear elevational view of the vibration absorber; FIG. 3 is a front elevational view of the vibration absorber; FIG. 4 is a right elevational view of the vibration absorber; FIG. 5 is a left elevational view of the vibration absorber; FIG. 6 is a bottom plan elevational view of the vibration absorber; and, FIG. 7 is a top plan view of the vibration absorber. The broken lines in the drawings illustrate portions of the vibration absorber which form no part of the claimed design.

1 Claim, 4 Drawing Sheets(56)
